UNITED STATES PATENT OFFICE.

ANDREW C. EDGAR, OF NEWTOWN SQUARE, PENNSYLVANIA, ASSIGNOR TO ABRAM COX STOVE COMPANY, OF PHILADELPHIA, PENNSYLVANIA, A CORPORATION OF PENNSYLVANIA.

COMBINED GAS AND COAL STOVE.

1,164,485.

Specification of Letters Patent. Patented Dec. 14, 1915.

Application filed September 14, 1911. Serial No. 649,259.

To all whom it may concern:

Be it known that I, ANDREW C. EDGAR, a citizen of the United States, residing in Newtown Square, county of Delaware, State 5 of Pennsylvania, have invented certain Improvements in Combined Gas and Coal Stoves, of which the following is a specification.

This invention relates to certain improvements in combined gas and coal stoves, and the object of the invention is to provide a water back for the stove, which is common to both the gas section and to the coal section of the stove.

15 The invention is particularly adapted for use in connection with a gas stove having a comparatively small coal section which can be used when it is desired to have a continuous supply of hot water.

20 In the accompanying drawings:—Figure 1, is a transverse sectional view of my improved combined gas and coal stove; Fig. 2, is a sectional plan view on the line 2—2, Fig. 1; Fig. 3, is an end view of my improved combined gas and coal stove; Fig. 4, is a detached view of one of the sections of the water heater; Fig. 5, is a detached view of a section of the water heater forming the water back of the fire pot; Fig. 6, is an enlarged sectional plan view of the burner; and Fig. 7, is a perspective view of the stove illustrating my invention.

A is the base of the stove.

B is the top which may have the usual 35 openings directly above the gas section under which are located the burners, with other openings directly above the coal section; these latter openings being closed by lids of the ordinary construction.

40 A' is the gas section of the stove and A² is the coal section. The gas section may have the usual oven and any number of burners desired, according to the type of stove to which the invention is applied.

45 The coal section does not extend to the full depth of the stove, and there is a chamber A³ back of the coal section for the water heating device. The coal section has the usual fire bricks a, a at the front and at 50 each side, and the section d of the heating device D forms the water back for the fire pot of the coal section, as clearly shown in Fig. 2. Directly under the fire pot of the coal section is the ash pit C having a door c.

55 The combustion chamber B' for the coal

section extends the full depth of the stove and over the space A³ for the water heating device; the products of combustion passing through the flue b at the back of the stove. The water heating device D consists, in the 60 present instance, of three sections d, d', d² of the form illustrated in Figs. 4 and 5. Each section d' and d² has a header e at the top and another header e' at the base connected by tubular members e², and the section d 65 has a portion f which extends across the back of the fire box, and depending from this section f are tubular members f' which communicate with a lower header f² as shown in Fig. 5. The sections are connected through nipples g at the top and nipples g' at the bottom so that the water is free to circulate through all of the sections of the water heater and, if it is desired, another 70 section may be added. The outer section d² has openings at the top and bottom closed with plugs h, h. On removing these plugs, nipples can be introduced to couple the additional section if more heating surface is 75 found necessary. The sections d', d² have lateral openings i, i' to which the circulating pipes I, I' are coupled. These circulating pipes extend to the boiler J which is of the horizontal type, in the present instance, and is supported on brackets resting on the 80 base of the stove in the usual manner.

Mounted on brackets m, in the present instance, is a burner M, located directly under the water heating device, and this burner is made as shown in Figs. 1 and 6 and has three 90 arms m' connected by a cross member m². The gas pipe p enters a funnel shaped casting P, which is connected to the end of the central arm m' and has a rotary damper p' for controlling the air supplied to the 95 burner. The arms m' are shaped as shown clearly in the sectional view, Fig. 1, and each has a perforated upper surface for the escape of gas. Air and gas enter the middle section and pass to the outer sections through the cross channel m²; the gas escaping on its way through the small openings. The gas is controlled by a suitable valve p² in the service pipe S, which also leads through a branch S' to the upper oven and through 100 a branch S² to the burners under the top plate of the range and the lower oven.

The compartment A³, in which the heater is located, has a vent opening t in the top plate T closed by a damper t' which, in the 110

present instance, is operated from the front of the range. This damper is closed when the gas is cut off and the coal fire is used, but when the gas is turned on to heat the water heating device, then this damper is opened to allow the chamber A³ to communicate through the flue b with the burner.

By the above description, it will be seen that I am enabled to construct a gas stove having a coal section provided with a water heating device which is common to both the gas section and the coal section. Furthermore, the heating surface of the device can be increased or diminished, as desired, by simply adding one of the sections or removing one of the sections.

I claim:—

1. The combination in a water heating device for a combined gas and coal stove, of a casing; a fire pot for the coal; a chamber back of the fire pot; a series of tubular water heating sections vertically arranged, one of said sections having a solid portion form-

ing the back of the fire pot; and a gas burner located within the chamber back of the fire 25 pot and under the series of sections.

2. The combination in a combined gas and coal stove, of a fire pot section; a chamber directly back of the fire pot section; a water heating device consisting of a series of tubular sections placed side by side and of a greater length than the height of the fire pot, said sections extending back of the ash pit; a gas burner located under the sections, the forward section of the series having a 30 35 solid portion forming the back of the fire pot so that the water section is heated either by the products of combustion from the coal or from the gas burners.

In testimony whereof, I have signed my 40 name to this specification, in the presence of two subscribing witnesses.

ANDREW C. EDGAR.
